INTERCEPTING PUSH BUTTON CONTROL SYSTEM

Ernest L. Gale, Yonkers, N. Y., assignor, by mesne assignments, to The Gurney Elevator Co., Honesdale, Pa., a corporation of Pennsylvania

Application August 6, 1926, Serial No. 127,522

65 Claims. (Cl. 187—29)

My invention relates to elevators and more particularly to electrically operated elevators controlled by a single automatic push-button system of circuits and apparatus.

5 One of the objects of the invention is to provide an improved system of circuits and apparatus whereby the car either in ascending or descending can be intercepted by actuation of any hall-buttons at any landings toward which the car is moving, said interception being effective by actuation of each of such hall-buttons only once, regardless of the number actuated for the purpose.

Another object of the invention is to embody 15 in conjunction with a dual system of control comprising a single automatic push-button system of circuits and a car switch system of control each operating independently to control the car, a novel system of circuits whereby the car either 20 in ascending or descending can be intercepted by actuation of any hall-buttons at any landing toward which the car is moving whether the car is under control of the push-button system or the car switch.

25 Another object of the invention is to arrange and coordinate the electrical system of control embodying the feature of intercepting the car, so that for any one direction of car travel, the hall or car push-buttons corresponding to the 30 landings which the car has passed are rendered inoperative to control the car, but the hall-buttons or car buttons corresponding to the landings toward which the car is moving remain operative to intercept and dispatch the car.

35 A still further object of the invention is to provide in conjunction with a single automatic push-button control system for intercepting the car, a novel system of circuits having a mode of operation whereby the car will reach the farthest 40 point to which it is dispatched before service operation in a reverse direction can be effected and when said farthest point is reached the car buttons are then given preference to dispatch the car in either direction, all the push buttons 45 at this time being rendered inoperative so long as the car gate remains in open position.

Other objects will appear more fully herein-after, the novel combinations of elements and arrangements of parts being fully pointed out in 50 the appended claims.

Referring to the drawings:

Fig. 1 illustrates in a diagrammatic manner, a system of electrical control for elevators whereby the car can be controlled independently by 55 either a single automatic push-button system of

circuits or by the car switch, with circuits arranged so that in either case the car can be intercepted by the hall push-buttons at any landing or landings toward which it is moving; and

5 Figs. 2 and 3 illustrate in a diagrammatic manner, a single automatic push-button system of electrical control having the intercepting feature and embodying automatic floor-stopping mechanism of a novel and modified construction.

Referring now to Fig. 1, the elements comprise 10 an elevator car C adapted for operation through any of the well known systems of roping or gearing by a hoisting motor M, illustrated herein as shunt wound, the system having a usual electro-mechanical brake B. Electro-magnetic reversing switches R and R' control the descending and 15 ascending directions of car travel respectively and a pair of direction relay switches A and A' control circuits for reversing switch windings 1 and 2 respectively. The present system is 20 adapted for dual control and for this purpose there is provided a manually operable car switch S, car 25 push-buttons 3, 4, 5 and 6, hall-buttons 7, 8, 9 and 10, the present system serving four floors, there being one button in both the car and in the hall 30 for each landing. When the car is under control of the push-button system a knife switch 11 in the car remains in closed position as illustrated and is thrown to an open position when the car 35 is to be under control of the car switch. Floor 30 relay switches are designated 14, 15, 16 and 17, and the floor relay magnets are designated 18. Each one of the floor relay switches such as correspond to the intermediate landings are provided with two pair of auxiliary back contacts 19 and 20, 35 and two pair of top contacts 21 and 22, but the switches corresponding to top and bottom landings have only one pair of back-contacts and two pair of top contacts. Automatically operable 40 floor stopping switch mechanism may be of any well known type, one of which is geared to a moving part of the hoisting apparatus, such as for example the drum shaft, and another type comprising independent switches fixed in the elevator 45 hatchway at each floor landing, and actuated by a cam on the car, the latter type being illustrated herein and being designated 23, 24, 25 and 26. Automatically operable up and down leveling switches are designated 27 and 28 respectively, 50 these switches being adapted to coact with their respective hatchway leveling cams 29 and 30 at each landing. These switches are rocked bodily by their respective bell-crank levers 31 when a winding 32 is energized to withdraw a double-faced cam 33 from rollers 34 to permit a spring 55

35 to effect rocking movement of the levers 31 and thereby rock the leveling switch rollers 36 to an inoperative position so as not to strike the leveling cams at the floors which the car passes by. When 5 the winding 32 is de-energized, a spring 37 urges the cam 33 downwardly and by so doing rocks the leveling switches bodily so that their rollers will be in a position to coact with their respective cams. By such coaction said leveling switches are actuated 10 to closed position in the event of the car overrunning or under-running a desired landing or during loading and unloading. Hatchway door contacts are designated 38 and the elevator car gate is provided with two sets of contacts 39 and 15 40, the former being closed with the gate in closed position and the latter being closed with the gate in open position. Electro-responsive switches 42 and 43 function as protective devices.

Operation of the parts through a complete cycle 20 as effected by push-button control will now be presented. With the elements in position as illustrated in Fig. 1, the car is at rest at the second floor landing, with the car gate and hatchway door open and the relay switches 16 and 17 being closed 25 indicates that the car is dispatched to both the 3rd and 4th landings. Let it be assumed that dispatch of the car to the 4th floor is effected by actuating the car-button 6 corresponding to said floor. The button 6 need be pressed only momentarily and closes a circuit for the relay winding 18, 30 which circuit includes the stopping switch 26, back contacts 44 on the down relay A and a winding 45 which is now energized to close the up relay switch A'. The circuit closed by pressing button 6 may be traced as follows,—from plus wire 160 through button 6 to wire 46, through relay winding 18 to wire 47 through floor stopping switch 26 to the wire 48 which is common to all of the up 35 stopping switch contacts, through back contacts 44 to wire 49, through relay winding 45 and thence to the minus line by way of wire 50. The 4th floor relay winding 18 now being energized actuates its switch arm to close top contacts 21 and 22 and open back contacts 19. The top contacts 21 40 of the 4th floor relay 17 close a self-holding circuit for the relay winding 18 which circuit may be traced from the plus wire 170 to wire 51, contacts 52 controlled by the switch 43, wire 53, which is a common feed wire for the hall push-buttons, 45 wire 54, floor relay contacts 21, wire 55 to a junction 56 with the wire 46, thence through relay winding 18 etc. to the minus line in a manner heretofore traced.

It will thus far be noted that actuation of the 50 push-button effects directly only the operation of the 4th floor relay switch 17 and the up direction relay A', and the self-holding circuit for the floor-relay winding 18 is controlled by the floor stopping switch 26.

60 It will be particularly noted that the reversing switch windings 1 and 2 are not included in either the push button or the self-holding circuit for the relay winding 18. However, the contacts 22 of relay 17 and also the contacts 57 of the "up" direction relay now close a circuit for the winding 2 of the up reversing switch R', that is, providing all the hatchway doors and also the car gate are closed, and said reversing switch will now close 65 to direct current to the hoisting motor and brake winding and in this manner effect operation of the car in an ascending direction. The circuit for the winding 2 of the reversing switch R' may be traced as follows: from plus wire 170 through 70 hatchway door and car gate contacts 38, 39 to

wire 58, switch 42 wire 63 including the leveling winding 32, contacts 22 of floor relay 17, wire 64 extending through each set of back contacts 20 in series associated with each floor relay designated 16, 15 and 14 and including contacts 95, 5 wire 65, thence through the up reversing switch winding 2 to wire 66, blade 67 of knife switch 11, wire 68, thence through contacts 57 to the minus line.

The car will now ascend from the 2nd to the 4th 10 floor, that is, still assuming that the 3rd floor relay switch 16 is open, and when the car is within a short distance of the 4th floor landing, the floor stopping switch 26 is automatically opened by movement of the car, thereby opening 15 the self-holding circuit for the winding 18 of the floor relay 17 and with all of the other floor relay switches now in open position; the up direction relay winding 45 will also be de-energized and both the floor relay switch 17 and the up direction relay A' will now open their top contacts and close 20 their back contacts.

In the present instance the circuit for the up reversing switch winding 2 is now opened at the 25 4th floor relay contacts 22, also at the up relay contacts 57, and the reversing switch R' will now open to discontinue the hoisting operation and effect application of the mechanical brake.

Coming now to the particular feature of the 30 invention which involves the matter of intercepting the car at one or more landings toward which the car is moving, let it be assumed again that the car is at the 2nd floor landing as shown and the 4th floor car-button 6 is pressed to dispatch the car to the 4th floor, in which case the floor 35 relay 17 is thereby closed and also the "up" direction relay A'. With all the hatchway doors and also the car door closed, the car will move in an ascending direction as heretofore pointed out. However, if either the hall-button 9 or car 40 button 5, which buttons correspond to the 3rd floor landing, is pressed before the car reaches said landing, the ascending car is thereby intercepted and will automatically stop at said landing, said interception being due to the operation 45 of the 3rd floor relay 16 to close its top contacts and open its bottom contacts. Now, as will be remembered, the feed circuit for the up reversing switch winding 2 as controlled by the 4th floor 50 relay switch contacts 22, included the back-contacts 20 of the 3rd floor relay and hence opening these back-contacts transfers the control of the "up" reversing switch winding feed-circuit 63 to the contacts 22 of the 3rd floor relay 16, said circuit being traced as before to the wire 63 and shunting therefrom at wire 69, contacts 22 of relay 16, wires 70 and 71, and forming a junction at 72 with the wire 64, through the back-contacts 20 of the floor relays 15 and 14 to wire 65, through 55 the "up" reversing switch winding 2 and so on to the minus line in the manner as heretofore traced. In order to maintain the continuity of the circuit for the "up" reversing switch winding when its feed is transferred from the 4th to the 3rd floor relay contacts 22, the fixed contact 20 is spring-pressed so as to follow up its coacting contact on the relay switch arm until the top contacts 22 are closed, and the fixed top contact of the set 22 is also spring-pressed to yield by movement of the switch arm to open circuit contacts 20 after the contacts 22 are closed. The fixed contacts 19 and 21 of each relay are constructed to have a mode of operation as just described 60 in connection with the contacts 20 and 22. 70

Continuing now, with the operation, the circuit as established by pressing the 3rd floor hall-button to intercept the car is as follows: from plus wire 170 to wire 51, contacts 52, wire 53, 5 through button 9, wires 73 and 74, through relay winding 18 of the 3rd floor relay 16, wire 75, through floor stopping switch 25 to the common wire 48 and so on through the "up" direction relay winding 45 and to the minus line as heretofore traced. The top contacts 21 of the floor relay 16 now close a self-holding circuit for the relay winding 18 which extends from the common feed wire 53, wire 76, top-contacts 21 and wire 77 which forms a junction at 78 with wire 74, the circuit 10 extending from thereon in a manner as just traced. When the car approaches within a short distance of the 3rd floor landing its movement will effect the automatic actuation of the 3rd floor stopping switch 25 to effect a stop of the 15 car at said landing. Opening the stopping switch 25 opens the self-holding circuit for the 3rd floor relay winding 18 and the relay switch 16 will now open its top contacts 21, 22 and close its bottom contacts. At this time it will be noted that 20 the circuit for the winding 45 of the "up" direction relay A' is maintained closed through the contacts 21 of the 4th floor relay 17, when the 25 3rd floor relay is de-energized and until the car reaches the 4th floor landing. In effect then it will be seen that regardless of the number of 30 interceptions of the car for any one direction of travel, it must complete its trip to the farthest point to which it is dispatched before it can be dispatched to travel in a reverse direction. This 35 reverse travel is prevented for the reason that back-contacts 578 are included in the circuit of the "down" relay winding 79, hence the down direction relay A cannot operate so long as the "up" direction relay remains energized.

40 Another important feature to be pointed out here is that the self-holding circuits for the windings of the floor relays are in parallel and shunting from common feed wire 53, hence all floor relay windings which have been energized for the 45 purpose of intercepting the car are maintained energized by their respective self-holding circuits, each relay being de-energized by actuation of the floor stopping switch corresponding thereto. This in effect means that regardless of the number 50 of buttons which are pressed to intercept the car at landings toward which it is moving, each button need be pressed only once for any one direction of car travel.

When the 3rd floor relay is de-energized to 55 effect a car stop, it opens at the contacts 22 the feed circuit for the up reversing switch winding and in order to break said circuit at these contacts before the back contacts 20 are closed, which sequence of operation is necessary in order to prevent a continuity of the circuit for the up reversing switch winding by reason of the 4th floor relay now being closed, the fixed contact 22 is provided with a dash-pot D to retard its return movement while at the same time the floor relay switch arm imparts a relatively quick movement to the contact 22 carried thereby.

The car is now stopped at the 3rd floor and the hoisting operation is not rendered effective again. 70 regardless of the fact that one or more of the floor relays are closed, it being remembered that the 4th floor relay is at this time closed, unless and until either the car gate or hatchway door is opened and again closed. However, it will be understood 75 that under certain conditions the push-buttons

remain operative to set the floor relays during the period of car stop and regardless of the position of the car gate or hatchway doors. In providing this protective feature the initial feed-circuit for the reversing switch winding 2 includes the hatchway door contacts 38, the car-gate contact 39, and the contacts controlled by switch 42. When the reversing switch closes, it closes contacts 80 and by so doing closes a circuit including the winding 81 of switch 42, wire 83, contacts 80, wires 84, 85 10 and at 86 forms a junction with the feed wire 63. A self-holding circuit for the winding 81 branches at a junction 87, then by wire 88, top contacts 89 of switch 42, thence through a relatively high resistance to the minus line. The winding 81 now 15 being energized opens the lower contacts of switch 42, opening at that point the original reversing switch winding feed circuit and as will be noted, when the reversing switch opens to open contacts 80, the circuit for the winding 81 will still be 20 maintained by way of wire 88 and contacts 89, this circuit including the car gate and hatchway door contacts. Thus it will be seen that when the 3rd floor relay 16 opens to open the up reversing switch winding circuit, said winding cannot be 25 again energized until the car door or hatchway door is opened and again closed. Such door-opening in effect de-energizes winding 81 so that the switch 42 will again close and with all 30 the hatchway doors and car gate closed, the original feed circuit which is independent of the reversing switch contacts 80 is restored and with the 4th floor relay now energized to close the reversing switch winding feed contacts 22, the 35 car will now travel to the 4th floor landing and be automatically stopped thereat and since this landing corresponds to the farthest point to which the car is dispatched, regardless of whether or not such landing is the limit of travel or an intermediate landing, the opening of the 40 floor relay switch opens the circuit for both the relay winding 18 and the "up" direction relay winding 45.

When the car is not under dispatch, which 45 condition corresponds to all the floor relays and also the up and down direction relays being in open position, the car if at an intermediate landing with all hatchway doors and the car gate closed, can be dispatched by the hall push-buttons to travel in either direction. On the other 50 hand, when the car is not under dispatch and is at rest at a landing, opening the hatchway door and car gate gives preference to the car buttons to dispatch the car in either direction, and renders the hall buttons inoperative to set or, in other 55 words, effect energization of any floor relay until the car gate is closed. This feature of the invention is accomplished by providing a car gate contact 40 to be closed by the opening of the car gate, and under the above assumed condition, that is, with both direction relays in open position with their back-contacts 82 closed, the latter together with the closed gate contact 40 now close a circuit including the winding 689 60 of the switch 43 whose normally closed contacts 52 are included in the hall push-button feed circuit. Winding 689 now being energized effects the opening of the contacts 52, thereby opening the feed wire 53 for the hall push-buttons and 65 in this manner render them inoperative to set any of the floor relays until the car gate is again closed. Thus a person in the car desiring to use the same is assured of not having it stolen from him so that he has complete control of the 70 75

car to establish travel thereof in the direction desired, and this direction must be established by pressing the desired car button prior to closing the car gate, and with all the hatchway doors closed, closing the car gate initiates the hoisting operation and again renders the hall push-button system operable to intercept the car at landings toward which it is moving.

The condition of this hall push-button feed circuit when the car is and is not under dispatch is to be distinguished here, for it is to be particularly noted that when the car is under dispatch, which condition corresponds to one or more of the floor relays being closed and one or 10 the other of the direction relays being in closed or actuated position; the hall-buttons remain operative to set their respective floor relays to intercept the car at the landings toward which it is moving, regardless of whether the car is stopped or the gates opened, and until the car 20 has reached its farthest point of dispatch and the hatchway door and car gate thereat opened and again closed.

When the car for any one direction of travel 25 is under dispatch, the car or hall push-buttons which correspond to the landings which the car has passed are rendered inoperative since when the up direction relay winding 45 is energized its back-contacts 578 open the down relay winding 30 circuit and likewise when the down direction relay winding 79 is energized its back-contacts 44 open the up relay winding circuit, and as will be remembered, each one of these circuits for reverse travel is maintained open until the car 35 has reached the farthest point to which it is dispatched and then the car cannot be started in a reverse direction until a hatchway and car gate has been opened and again closed.

Thus far it will be observed that the top contacts 40 of the floor relays are connected by parallel wires shunting from the common feed wire 63, and the circuits for the reversing switch windings after passing through any one of the intermediate floor relay contacts 22, includes one 45 or the other series of back-contacts 19 or 20 (depending on the direction of car travel) of all the floor relays corresponding to the floor or floors which the car has passed.

Hence it will be seen that with this arrangement 50 of circuits for the reversing switch windings the car will stop in succession at landings toward which it is moving which correspond to the hall-buttons pressed for the purpose of intercepting the car, but without opening the closed direction 55 relay switch, except at the point of ultimate dispatch.

In view of the complete and detailed description 60 of the circuits and mode of operation as already given with respect to ascending direction of car travel, it is thought unnecessary to give a detailed description of the elements for descending direction of car travel other than to mention that the back-contacts 19 of the floor relays 17, 65 16 and 15 control the circuit of the down reversing switch winding 1 in a manner to effect interception of the descending car.

If it may be desired to effect leveling of the 70 car platform with landings and to maintain the platform level during loading and unloading, such result can be obtained by adding to the system the leveling switch controlling mechanism having a mode of operation as follows: the actuating winding 32 for the cam 33 is contained in 75 the feed circuit 63 and is therefore energized

and de-energized simultaneously with the reversing switch windings excepting during the operation thereof for leveling. Hence when an automatic floor stopping switch functions to discontinue the hoisting operation, this winding 32 is 5 de-energized and cannot be energized again until a hatchway and car door is opened and again closed. Therefore, when the hoisting operation is discontinued as by operation of the automatic 10 stopping switch, the leveling switch mechanism is then rendered operable to effect the automatic leveling operation as effected by downward movement of the cam 33 to rock the levers 31 and so rock both of the leveling switches bodily to bring their leveling rollers 36 into engagement 15 with one or the other of the leveling cams 29 or 30. Assume now the car is ascending in the cam zone toward the 2nd landing and the roller 36 engages the up cam 29. Such co-action between the cam and roller closes the leveling switch contacts 91 and 92 to close a circuit for the up reversing switch winding 2, thereby effecting operation of the up reversing switch to control the hoisting motor to continue movement of the car toward the landing and when the car is substantially level therewith the roller 36 rides down the incline face of the leveling cam 29 and permits a spring 93 to open the leveling switch to effect stop of the car. In the event of the car 20 now over-running the landing, the roller 36 of 25 the car leveling switch is brought into engagement with the cam 30 and such coaction closes the down leveling switch 28 to effect operation of the down reversing switch R to reverse the movement of the car and return it to a level with the 30 landing. The feed circuit for the reversing switch windings is independent of the push-button feed circuit 63 and the circuit for the up reversing switch winding as controlled by the up leveling 35 switch may be traced as follows: from the plus 40 wire 180, contacts 92, wire 181, through the up reversing switch winding 2, wires 66 and 182, and thence through the leveling switch contacts 91 to the minus line.

Any tendency of the car to move away from 45 a level with the landing by reason of stretch or contraction of the hoisting cables due to loading or unloading, renders one or the other of the leveling switches operative to return the car to the landing.

The leveling switch mechanism controls feed-circuits for the reversing switch windings which are independent of the push-button system of circuits, it being desirable when the leveling switch mechanism is rendered operable to disconnect the push-button system of circuits such as control the reversing switch windings from the leveling switch feed-circuits and to accomplish this result the push-button controlled feed-circuits for 60 the up and down reversing switch windings are opened at the contacts 94 and 95 controlled by an electro-magnet 96 whose circuit 97 is opened by normally closed contacts 98 when either leveling switch engages its respective leveling cam 29 or 30. 65

In order now to render the system operable for 70 car switch control, the knife switch 11 in the car is first thrown to open position to disassociate the control of the reversing switch windings from the up and down direction relays A and A' and by shunting these circuits around the knife switch 11 as effected by wires 101 and 102 and connected them to the car switch contacts 99 and 100, said 75 reversing switch circuits are thereby rendered operable to be opened and closed at will by opera- 75

- tion of the car switch. Before taking up control of the system by car switch operation the car buttons 6 or 3 should first be pressed to establish a feed for the reversing switch winding 5 through one of the direction relay switches A or A' corresponding to the direction of car travel desired. Say, for example, car button 6 is operated, the 4th floor relay switch 17 and up relay switch A' will operate and while the feed circuit 10 for the reversing switch winding 2 is closed at the 4th floor relay contacts 22, it is, however, opened at the car switch, so that by operation of the car switch segment to engage contacts 100 and 103, said circuit is completed to effect energization 15 of the up reversing switch winding and in this way control the ascending hoisting operation of the car, and as will be evident, the car can be stopped at any desired landing at the will of the operator by centering the car switch. 20 The circuit for the winding of the up reversing switch R' may be traced as follows: from the plus wire 170, door and car gate contacts 38 and 39 to wire 58, switch 42, wire 63, contacts 22 of 25 contacts 20 in series of each floor relay 16, 15 and 14, the circuit including the contacts 95, wire 65, through the winding 2 of the reversing switch R', wire 66 to junction 104, wire 102, thence by way of the car switch contacts to the minus line. It will be observed now that this 30 circuit for the reversing switch winding included the series of floor relay contacts 22, hence it will be seen that the car can be intercepted at any of the landings toward which it is moving even though the car switch is held in "on" position, 35 by pressing a button at any of said landings to effect operation of the floor relays and in this way the control of the feed circuit for the reversing switch winding is transferred to the various relays corresponding to the intercepting hall-buttons and the car will stop in succession at the landings corresponding to the hall-buttons pressed. It will be obvious that the leveling switch mechanism becomes operative automatically to level the car platform subsequently to 40 the discontinuation of the hoisting operation whether effected by centering the car switch or by the automatic floor stopping switches which are caused to function if the car is intercepted by operation of a hall-button or buttons. 45
- With car switch control the protective features are the same as for push-button control as to those features which prevent operation of the car until all the hatchway doors and the car gate are closed, and which prevent operation of the car subsequently to a landing stop, unless and until a hatchway door and car gate is first opened and again closed. 50
- Referring now to Fig. 2, the push-button system of circuits is substantially identical with the system illustrated in Fig. 1. However, in Fig. 2, automatically operable floor stopping switch mechanism is of a modified form consisting of a tape forming two current carrying sections 150 and 151 which through coacting contact clips 152 at each floor landing, render the push-button circuits inoperative at landings which the car has passed by, while the push-buttons corresponding to landings toward which the car is moving, remain operative to intercept and dispatch the car. One of the ends of each of the two tape sections is attached to a contact such as 153, 153', the two ends having a gap formed therebetween so that with a car at any one landing the contact clip at such landing will assume 55 a neutral position with respect to the two current carrying sections. The two sections are connected to move with the car by securing the contacts 153, 153' thereto at 154 and extend from said contacts in opposite directions around 60 guide sheaves 155 at the top and bottom of the hatchway, their other ends being connected together at a point 156 by some suitable material which insulates the sections from each other, the two sections being movable by the car in a manner as though endless. 65
- The circuit for each floor relay as designated 47, 75, includes its respective contact clips 152. 70 The upper and lower sections 151 and 150 of the tape sections provide a common feed for the up and down direction relay windings 45 and 79 respectively, the circuit for the winding 45 extending from the contact 153', wire 157, back contacts 44, on down relay A, wire 158, thence through winding 45 to the minus line. The circuit for the winding 79 extends from the contact 153, wire 159, back-contacts 78, wire 160, thence through winding 79 to the minus line. 75
- With the car ascending from the 1st floor, it will be evident that the floor contacts 152 at all 25 the landings toward which the car is moving are in electrical contact with the upper section 151 of the tape and in this way all the push-buttons at said landings are rendered operable to dispatch the car and these circuits are the same 30 as in Fig. 1 to permit intercepting of the car at any landings toward which it is moving. As the car in ascending reaches each landing, the movement of the tape sections by the car causes the upper or live section to disengage the clips at 35 such landing, and in this way any floor relay winding corresponding to the button pressed to intercept is de-energized, but the upper section of the tape remains alive to maintain the circuit for the up direction relay until the car has 40 reached the farthest point to which it is dispatched whereat the floor relay contacts provide the feed for said tape. The ascending car as it moves away from each intermediate landing, brings the lower tape section 150 into engagement with the clip 152 at such landings, and this section remains dead which in effect renders the push-buttons inoperative at the floors which the car has passed, and such push-buttons are inoperative at this time because with the car ascending the circuit for the down direction relay winding is open and the up relay back-contacts 78. 50
- Thus from the description herein given it will be seen that these tape sections and coacting elements function to control the circuits of the push-button system in identically the same manner as do the cam operated floor stopping switches in the hatchway as illustrated in Fig. 1. 55
- In the modification illustrated in Fig. 3, the 60 circuits for the operating windings of the reversing switch mechanism are controlled jointly and directly by both the floor stop switches and the floor relay switches, whereas in Fig. 1, said circuits are controlled directly by only the floor relays and indirectly by the floor stop switches by the provision of three sets of contactors for each relay for each intermediate landing, and dash-pots are employed to effect control of the 65 circuits in proper order or sequence. By such joint control, the control of the circuits in proper order or sequence is obtained without the use of dash-pots to effect that same results as in Fig. 1. 70 In adapting the floor stop switches for such use, 75

each is provided with relatively long and short segmental contactors 161 and 162 respectively, controlling respectively the circuits for the floor relay windings and the windings of the reversing switches.

In operation, the floor relay switches corresponding to landings toward which the car is moving remain set to intercept the car thereat by momentarily pressing the buttons only once for any one direction of car travel, and one or the other of the direction relays remains closed so that car reversal cannot ordinarily be effected before the car reaches any landing which corresponds to the farthest point to which it is dispatched by either the car or hall-buttons, regardless of the number of intermediate stops.

Now as to the mode of operation of the floor relay switches to control the circuits for the reversing switch windings jointly with the floor stop switches, the "up" and "down" feed wires 163 and 164 after passing through auxiliary contacts 165, 166 respectively controlled by the direction relays A', A include their "up" and "down" floor relay back contactors 20 and 19 in series, which contactors (together with protective contactors not shown) when all closed complete the circuits for their respective windings as determined by whichever direction relay is closed, and by providing wires 167 in shunt to said series connection, and controlling the same by the floor stop switch segments 162 together with their coacting fixed contactors. Car stops will thereby be effected successively at all landings toward which the car is moving whose corresponding floor relay switches are open as effected by push-button control so that each floor relay by opening thereby renders the stop operation subject to the control of its corresponding floor stop switch which by actuating its segment will thereby open the energizing circuit of whichever reversing switch winding is energized. The shorter segment 162 of each floor stop switch will disengage its fixed contactor to de-energize the reversing switch winding before the longer segment 161 open-circuits the floor relay winding to permit its back-contactors to close, and in this manner a time period is introduced to permit the reversing switch to open and render the protective devices effective before the floor relay back-contacts close, so that the circuit for the reversing switch winding cannot again be closed until the hatchway and car doors are opened and again closed.

It will be understood, of course, that in substituting this modified arrangement for that illustrated in Fig. 1, the reversing switch winding circuits will include the car and hatchway door contacts and other protective devices as illustrated in Fig. 1, but not illustrated in Fig. 3, since their function has already been described in detail in connection with said Fig. 1, and in Fig. 3 only such circuits have been illustrated as are necessary for a clear understanding thereof.

Having thus described my invention, what is claimed is:

1. In a push-button system of control for intercepting the car, the combination with the car, car gate contactors, push-button controlled circuits and apparatus to effect automatic stops in succession at landings toward which the car is moving by pressing the buttons corresponding thereto only once for any one direction of car travel at any time prior to the car reaching such landings, and means to render the hoisting operation inoperative unless and until said car gate contactors are opened and closed subsequently to each of said automatic stops.

2. In a push-button system of control for intercepting an elevator, the combination with the car, car gate contactors, and push-button controlled circuits and apparatus to effect automatic stops in succession at landings toward which the car is moving by pressing the buttons corresponding thereto only once for any one direction of car travel, the car movement in each instance being initiated by closing said car gate contactors.

3. In a push-button system of control for intercepting an elevator, the combination with the car, car gate contactors, push-button controlled circuits and apparatus to effect automatic stops at landings toward which the car is moving by pressing the buttons corresponding thereto only once for any one direction of car travel and at any time prior to the car reaching said landings, the hoisting operation in each case being initiated by closing said car gate contactors, and means to render such hoisting operations inoperative unless said car gate contactors are opened subsequently to each of said automatic car stops.

4. In a push-button system of control for intercepting the car, push-button controlled floor relays and switches all corresponding to the landings toward which the car is moving being energizable at any time and being maintained energized uninterruptedly from the time of initial energization and until the car reaches landings corresponding thereto, and means whereby the closed relay switch corresponding to the landings nearest to the car position together with the series of open floor switches corresponding to the floors which the car has passed are rendered effective to control the hoisting operation automatically to effect a stop of the car at said nearest landing, and each closed relay switch by opening thereby transferring control of the hoisting operation to the nearest closed floor switch corresponding to a landing beyond.

5. In a push-button system of control for intercepting the car, the combination with the car, a hoisting motor and means to control the hoisting operation of said motor comprising three or more switches, the closed switch corresponding to the landing nearest to the car position together with the open switches corresponding to the landings passed by, being rendered operable to control the hoisting operation and effect an automatic stop at said nearest landing, and each closed switch by opening, thereby transferring the control of the hoisting operation to the nearest already closed switch corresponding to a landing beyond.

6. In a push-button system of control for intercepting the car, the combination with the car, a hoisting motor, and means to control the operation of said motor comprising a series of floor relays capable of being energized substantially at the same time, means to de-energize said floor relays in succession, and means whereby the energized relay corresponding to the landing nearest to the car position, together with de-energized relays corresponding to the landings passed by are rendered operable to control the hoisting operation and effect an automatic stop at said nearest landing and each relay when deenergized thereby operating to transfer the control of the hoisting operation to the nearest already energized relay corresponding to a landing beyond.

7. In a push-button system of control for intercepting the car, the combination with the car, a hoisting motor, car gate contactors, means to

- control the operation of said motor comprising a series of floor switches capable of being closed substantially at the same time, means to open said floor switches in succession, means whereby 5 the closed floor switch corresponding to the landing nearest to the car position together with the open floor switches corresponding to the landings passed by are rendered operable to control the hoisting operation and effect an automatic stop 10 at said nearest landing, and each closed switch by opening thereby transferring the control of the hoisting operation to the nearest already closed floor switch corresponding to a landing beyond, and means whereby said transfer is rendered in- 15 effective to initiate the hoisting operation unless and until said car gate contactors are opened and again closed subsequently to each car stop.
8. In a push-button system of control for intercepting an elevator, the combination with the 20 car, a hoisting motor, car gate contactors, a plurality of closed floor switches, floor stopping switch mechanism automatically to open said closed floor switches successively, electro-magnetically operated reversing switch mechanism to 25 control the hoisting motor, and means whereby the closed floor switch corresponding to the landing nearest to the car position is rendered operable to control the operation of a reversing switch corresponding to car travel, each of said floor 30 switches by opening thereby transferring the control of the reversing switch mechanism to the nearest already closed floor switch, corresponding to a landing beyond, and means whereby said transfer of control cannot effect a hoisting operation unless and until said car gate contactors are 35 opened and again closed subsequently to each car stop.
9. In a push-button system of control for intercepting an elevator, the combination with the car, 40 car gate contactors, a hoisting motor, a plurality of closed floor switches, direction switches, reversing switch mechanism to control the hoisting operation, means automatically to open said floor switches successively, means to control the operation of said reversing switches whereby said opening of each floor switch automatically transfers the control of the reversing switch mechanism to the nearest closed relay switch corresponding to the floor beyond, and at the same time 45 effects automatic car stops in succession at landings corresponding thereto, and means whereby said transfer of control of the hoisting operation cannot effect a continuation of the hoisting operation unless and until the car gate contactors are 50 opened and closed subsequently to each car stop.
10. In a push-button system of control for intercepting an elevator, the combination with the car, car gate contactors, a hoisting motor, push-buttons corresponding to the landings served, 55 closed floor switches so rendered by momentary actuation of said push-buttons, direction switches controlled to be closed by the closing of any floor switch and maintained closed uninterruptedly thereafter until all of said relay switches are 60 opened, reversing switch mechanism to control the hoisting operation, means automatically to open said floor switches successively, means to control the operation of said reversing switch mechanism whereby said opening of the floor 65 switches effects car stops in succession at the landings corresponding thereto, and at the same time transfers the control of the hoisting operation to the nearest already closed floor switch corresponding to a landing beyond, and means 70 whereby said transfer of control of the hoisting 75
- operation cannot effect continuance of the hoisting operation unless and until the car gate contactors are opened and again closed.
11. In a push-button system of control for intercepting an elevator, the combination with the 5 car, a hoisting motor, reversing switch mechanism to control the hoisting operation of said motor, automatically operable floor stopping switch mechanism and means controlled thereby automatically to effect car stops successively at landings towards which the car is moving, comprising a series of closed switches, and an energizing circuit for said reversing switch mechanism closed by the closed switch corresponding to the landing nearest to the car position, each switch when 10 opened being included in series with said circuit, and by so opening, thereby opening the energizing circuit of the reversing switch mechanism, and transferring the control of said reversing switch control to the nearest closed switch correspond- 15 ing to a landing beyond.
12. In a push-button system of control for intercepting an elevator, the combination with the car, car gate contactors, a hoisting motor, reversing switch mechanism to control the hoisting operation of said motor, automatically operable floor stopping switch mechanism and means controlled thereby automatically to effect car stops successively, at landings toward which the car is moving, comprising a series of closed 20 switches, and an energizing circuit for said reversing switch mechanism closed by the closed switch corresponding to the landing nearest to the car position, each switch when opened being included in series with said circuit, and by so 25 opening thereby opening the energizing circuit of the reversing switch mechanism, and transferring the control of said reversing switch circuit to the nearest closed switch correspond- 30 ing to a landing beyond, and means independent of 35 said switches to maintain said energizing circuit open when each transfer of control thereof is made, unless and until the car gate contactors are opened and again closed.
13. In a dual system of control for elevators, 40 the combination with the car, a hoisting motor, a push button control system of circuits and apparatus to start the car and to intercept the car to effect automatic stops at landings intermediate the farthest landing to which the car is dispatched by said push button control system, and a car switch to control said circuits to start and stop the car at will.
14. In a dual system of control for intercepting an elevator, the combination with the car, a 45 hoisting motor, a dual control system comprising a push-button system of control circuits and a car switch system of control circuits, said circuits being correlated so that the car can be intercepted and automatic stops effected by selective operation of the buttons corresponding to landings intermediate the car position and the farthest landing to which the car is dispatched whether by push-button or car switch operation.
15. In a dual system of control for elevators, 55 the combination with the car, a hoisting motor, means to control the hoisting operation of said motor comprising a series of switches controlled automatically by the car movement, car switch 60 controlled circuits correlated with said switches to control the car at will, and push-button controlled means to render said switches effective selectively to be operated by movement of the car to effect automatic stops at any landings to- 65 70 75

ward which the car is moving while the car is under control of the car switch.

16. In a dual system of control for elevators, the combination with the car, a hoisting motor, means to control the hoisting operation of said motor comprising a series of switches controlled automatically by movement of the car, car switch controlled circuits corelated with said switches to control the car at will, push-button controlled 10 means to render said switches operable selectively to be actuated by movement of the car to effect automatic stops at landings towards which the car is moving while under car switch control.

17. In a dual system of control for intercepting a car, the combination with the car, reversing switch mechanism having a winding, a circuit for said winding including switches in series with each other, push-button controlled apparatus to control said circuit to dispatch the car selectively to desired landings, and a car switch to control said circuit at will to effect stops, said push-button controlled apparatus being effective during car switch control to intercept the car at desired landings regardless of the position of said car switch, by opening said reversing switch winding circuit.

18. In a dual system of control for elevators, the combination with the car, a hoisting motor, means to control the hoisting operation of said motor comprising push-button controlled series of switches to effect automatic stops in succession at landings intermediate the farthest landing to which the car is dispatched, and car switch controlled circuits corelated with said series of switches to control the hoisting operation to start and stop the car at will, while at the same time said push-button controlled switches remain effective to effect automatic stops at landings toward which the car is moving independently of the car switch.

19. In a dual system of control for intercepting a car, the combination with push-button controlled floor relay switches, all of those corresponding to landings toward which the car is moving being energizable at any time and being maintained energized uninterruptedly thereafter until landings corresponding thereto are reached, electro-magnetically operated reversing switches, circuits therefor controlled by said floor switches to effect car stops successively at landings corresponding to said actuated floor switches, a car switch to control said reversing switch circuits independently of push-button operation which latter at the same time remains operable 55 to intercept the car and effect automatic stops independently of the car switch at landings toward which the car is moving.

20. In a combined car switch push-button system of control for intercepting the car, the combination with the car, a hoisting motor, reversing switches each having a winding to control the hoisting operation of said motor, direction switches in the circuits of said windings, push-button controlled floor relays maintained energized uninterruptedly after initial energization at any time during travel of the car toward landings corresponding thereto are reached, the circuits of said reversing switches being controlled by said floor switches to effect car stops successively at landings corresponding to said actuated floor switches, a car switch to control said reversing switch circuits independently of push-button operation which latter at the same time remains operable to intercept the car and effect automatic stops independently of the car

switch at landings toward which the car is moving.

21. In a dual system of control for intercepting an elevator, the combination with the car, a hoisting motor, reversing switch mechanism to control the hoisting operation of said motor, automatically operable floor stopping switch mechanism, means controlled thereby automatically to effect car stops successively at landings toward which the car is moving, comprising a series of closed switches, an energizing circuit for said reversing switch mechanism closed by the closed switch corresponding to the landing nearest to the car position, each switch when opened being included in series with said energizing circuit and by so opening thereby opening the energizing circuit of the reversing switch circuit to the nearest closed switch corresponding to a landing beyond, a manually operable car switch to open and close said reversing switch mechanism circuit at will, 20 push-buttons corresponding to landings served, and means controlled thereby to control said reversing switch mechanism circuit to intercept the car by effecting the automatic opening of said circuit at any landings toward which the car is moving while under the control of said car switch.

22. In a system of control for intercepting an elevator, the combination with the car, car gate contactors, a hoisting motor, reversing switches 30 for said motor each having a winding, and means to control said reversing switches to effect automatic stops successively at all landings toward which the car is moving comprising switches corresponding to the number of floors served, connected in series and including a winding of one of said reversing switches, all of said switches corresponding to landings in the direction corresponding to car travel being operable to closed position at any time subsequently to such direction of travel being established, the closed switch corresponding to the landing nearest to the car controlling the reversing switch winding exclusively of the closed switches corresponding to the landings beyond, each closed switch when 45 opened being included in said series circuit with a reversing switch winding and by such opening, thereby effecting an automatic car stop and transferring the feed circuit for said reversing switch winding to the next nearest closed series switch, 50 and means to maintain said feed circuit open when each transfer is effected, unless and until the car gate contactors are opened and again closed.

23. In a system of control for intercepting an elevator, the combination with the car, a hoisting 55 motor, reversing switches for said motor each having a winding, and means to control said reversing switches to effect automatic stops successively at all landings towards which the car is moving, comprising switches controlled by movement of the car which in open position are in a series circuit including a reversing switch winding, each switch when closed thereby opening said series circuit.

24. In a system of control for intercepting an elevator, the combination with the car, car gate contactors, a hoisting motor, reversing switches to control said motor, means to control said reversing switches to effect automatic stops 70 successively at all landings towards which the car is moving, comprising a number of closed switches corresponding to landings toward which the car moves opened automatically by movement of the car, the closed switch corresponding to the land- 75

ing nearest the car position, controlling the reversing switch exclusively of the closed switches corresponding to the landings beyond, each closed switch by opening thereby rendering the closed switch corresponding to a landing beyond operable to control said reversing switch to effect a hoisting operation, and means operable when each of said switches opens to effect a car stop to prevent said closed switch at a landing beyond from continuing the hoisting operation unless and until the car gate contactors are opened and again closed.

25. In a system of control for intercepting an elevator, the combination with the car, car gate contactors, a hoisting motor, electro-magnetically operated reversing switches to control said motor, push-button controlled switches to control said reversing switches to effect automatic stops selectively at landings toward which 15 the car is moving and which are intermediate a landing to which the car is already under dispatch, and means to render all of said switches even though closed, corresponding to the landings beyond those nearest to car position 20 effective to continue the hoisting operation until subsequently to a car stop at said nearest landing and unless the car gate contactors are open and again closed subsequently to said stop.

26. In a dual control system for intercepting 30 an elevator, the combination with the car, a hoisting motor, a push-button and car switch system of circuits corelated so that the car can be intercepted and automatic stops effected by selective operation of the buttons corresponding 35 to landings intermediate the farthest landing to which the car is dispatched whether by push-button or car switch operation, and means operable for each car stop whether effected by push-button or car switch control automatically 40 to control said hoisting motor to level the car with the landing in the event of the car overrunning and underrunning the same.

27. In a dual control system of intercepting 45 an elevator, the combination with the car, a hoisting motor, push-button and car switch system of circuits corelated so that the car can be intercepted and automatic stop effected by selective operation of the buttons and started and stopped by the car switch independently of the 50 buttons at any point intermediate the farthest landing to which the car is dispatched by push-button operation and automatically operable leveling switch mechanism comprising an electro-responsive device to render the leveling 55 mechanism ineffective during the hoisting operation as controlled by either the push-buttons or car switch.

28. In a push-button system of control for 60 intercepting the car, the combination with the car, car gate contactors, a hoisting motor, a reversing switch having a winding, means to control a circuit for said winding including a plurality of closed switches opened successively by movement of the car, said switches being in series with each other so that said successive opening thereof effects successive stops at landings corresponding thereto, each switch by opening thereby transferring the control of said reversing switch circuit to the already closed switch corresponding to the next adjacent floor, and means whereby said transfer of the control of 65 said circuit cannot initiate the hoisting operation unless and until said car gate contactors

are opened and again closed subsequently to each car stop.

29. In a dual system of control for intercepting 5 an elevator, the combination with the car, a hoisting motor, a reversing switch mechanism having a winding, a circuit for said winding, means to control said circuit comprising a push-button system of circuits and a car switch system of circuits, each system being operable independently to control the start and stop of the 10 car, and means to render the car switch effective to control said reversing switch circuit to initiate the hoisting operation, while at the same time said push-button system remains effective to 15 intercept the car at any landings toward which the car is moving by opening said reversing switch winding circuit independently of the car switch.

30. In a dual system of control for intercepting 20 an elevator, the combination with the car, a hoisting motor, reversing switch mechanism having a winding, a circuit for said winding, a car switch to control said circuit to start and stop the car at will, and a push-button system of circuits operable selectively to effect 25 automatic stops at landings toward which the car is moving by opening said reversing switch circuit while under control of said car switch.

31. In a dual system of control for intercepting 30 an elevator, the combination with the car, a hoisting motor, a system of control therefor comprising a selective push-button system of circuits and a car switch system of circuits operable jointly to enable the car to be 35 intercepted and automatic stops effected by selective operation of the push-buttons while the car is under car switch control, and means to render the car switch circuits inoperative so that the push-button system is operable exclusively to dispatch and effect automatic intercepting stops 40 of the car.

32. In a push-button system of control for 45 intercepting an elevator, the combination with the car, a hoisting motor, a reversing switch mechanism having a winding, means to control a circuit for said reversing switch winding comprising a plurality of switches all of which in one position close an energizing series circuit for said reversing switch winding and when in another position close circuits shunting from 50 said series circuit of adjacent switches, and by moving to said other position thereby opening said series energizing circuit, and push-button controlled means operable by pressing buttons only once momentarily and at any time subsequently to direction of car travel being established to render said plurality of switches operable to control said reversing switch mechanism to effect automatic successive stops at 55 landings intermediate the car position and the farthest landing to which the car is dispatched.

33. In a push-button system of control for 60 intercepting an elevator, the combination with the car, push-button controlled relays all of which correspond to landings toward which the car is moving being maintained set to effect car stops by actuation of the buttons only once for any one direction of car travel, reversing switch mechanism having an operating winding, and 65 contacts connected in series and controlled in accordance with car position and by said relays selectively to effect car stops.

34. In a push-button system of control for 70 intercepting an elevator, the combination with the 75

car, a hoisting motor, reversing switch mechanism for the motor having an operating winding, and means to control said reversing switch mechanism to effect automatic stops selectively at landings toward which the car is moving comprising push-button controlled floor relay switches connected in series by a circuit including said reversing switch winding.

35. In a push-button system of control for intercepting an elevator, the combination with the car, a hoisting motor, reversing switch mechanism for the motor having an operating winding and push-button controlled floor relay switches connected in series by a circuit including said reversing switch winding, up and down direction switches having windings energizable by said buttons, and self-holding circuits controlled by said floor relays and including said direction switch windings to maintain same energized one at a time uninterruptedly until the car reaches its farthest point of dispatch regardless of the number of intermediate car stops effected by interruption of said circuit.

36. In a push-button system of control for intercepting an elevator, the combination with the car, a hoisting motor, reversing switch mechanism for said motor having an operative winding, push-button controlled floor relay switches connected in a series circuit including said reversing switch winding, up and down direction relay windings energizable by said buttons, and self-holding circuits for said floor relays including said direction relay windings one at a time, each floor relay switch controlling its own self-holding circuit independently of the others so that all floor relay switches which correspond to landings toward which the car is moving are set and maintained in such position by only a single momentary operation of the button and a direction relay is thereby maintained energized uninterruptedly until the landing corresponding to the farthest point to which the car is dispatched is reached regardless of the number of intermediate stops effected by interruption of said series circuit.

37. In a push-button system of control for intercepting an elevator, the combination with the car, a hoisting motor, reversing switch mechanism therefor having an operating winding, push-button controlled floor relay switches connected in a series circuit including said reversing switch winding, circuits shunting from each floor relay switch controlled in accordance with car position and direction switches maintained closed uninterruptedly until the landing corresponding to the farthest point of dispatch is reached regardless of the number of intermediate car stops.

38. In a push-button system of control for intercepting an elevator, the combination with the car, a hoisting motor, reversing switch mechanism therefor having an operating winding, push-button controlled floor relay switches connected in series by a circuit including said reverse switch winding, said floor relay switches for all landings toward which the car is moving being settable at any time to open said series circuit, each being maintained set uninterruptedly until it effects car stop at its corresponding landing, circuits shunting from each relay switch controlled in accordance with car position, and direction switches controlled by said buttons and maintained closed uninterruptedly until the landing corresponding to the farthest point of dispatch is reached regardless of the number of intermediate stops.

39. In a push-button system of control for intercepting an elevator, the combination with the car, a hoisting motor, reversing switch mechanism having an operating winding, a circuit for said winding including said floor switches in series and circuits shunting around said series connected floor switches so that the circuit for said reversing switch winding relative to car position includes the floor switches in series corresponding to the landings which the car has passed by, and by way of the shunt circuit around the set floor switch corresponding to the nearest landing toward which the car is moving so that said nearest switch by being set thereby opens said series circuit to render all set floor switches at landings beyond ineffective and renders its shunt circuit effective to control car stop.

40. In a push-button system of control for intercepting an elevator, the combination with the car, a hoisting motor, reversing switch mechanism having an operating winding, a circuit for said winding including said floor relay switches in series and circuits shunting around said series connected floor relay switches so that the circuit for said reversing switch winding relative to car position includes the floor relay switches in series corresponding to the landings which the car has passed by, and by way of the shunt circuit around the set floor relay switch corresponding to the nearest landing toward which the car is moving, so that said nearest switch by being set thereby opens said series circuit to render all set floor relay switches at landings beyond ineffective and renders its shunt circuit effective to control car stop, and contactors controlled in accordance with car position to control said shunt circuits.

41. In a push-button system of control for intercepting an elevator, the combination with the car, a hoisting motor, control means therefor including direction switches, reversing switch mechanism therefor having an operating winding, push-button controlled direction switches maintained closed uninterruptedly until any one landing which corresponds to the farthest point of dispatch is reached, and a floor stop switch for each landing to control said operating winding to open said reversing switch mechanism to effect car stops independently of said direction switches, at any landings intermediate car position and said farthest landing toward which car travel is directed.

42. In a push-button system of control for intercepting an elevator, the combination with the car, a hoisting motor, up and down direction switches having operating windings, push-button controlled floor switches having self-holding circuits, each switch controlling its self holding circuit independently of the others, said self-holding circuits including said up or down direction switches dependent on the position of the car with respect to the button pressed so that all floor switches corresponding to landings toward which car travel is directed as determined by said direction switches are settable by momentary actuation of the button only once for any one direction of car travel to control car stops and such direction switch as is closed being maintained in closed position.

such position uninterruptedly by the floor switch corresponding to the farthest landing to which the car is dispatched regardless of the number of intermediate landing stops, up and down reversing switches each having an operating winding, and circuits therefor controlled by said floor switches, said circuits being opened to effect car stops independently of said direction switches.

43. An elevator system comprising an elevator car, a manual switch on the car for each of a plurality of landings, an additional switch on the car normally to control the car, and hoisting motor and brake control means arranged so that joint actuation of a manual switch for a landing other than for the landing at which the car is stopped and said additional switch, is necessary to cause start of the car.

44. An elevator system comprising an elevator car, a manual switch on the car for each of a plurality of landings, an additional switch on the car normally to control the car, hoisting motor and brake control means so arranged that joint actuation of a manual switch for a landing other than that at which the car is stopped and said additional switch, is necessary to cause start of the car, and being responsive at the same time to said manual switches for each of said landings to cause stops of the car at landings successively in their natural order.

45. An elevator system comprising an elevator car, a manual switch on the car for each of a plurality of landings, an additional switch on the car normally to control the car, hoisting motor and brake control means responsive only to joint actuation of a switch for one of said landings and said additional switch, to cause start of the car, and responsive at the same time to cause automatic stops of the car at landings for which switches are actuated.

46. An elevator system comprising an elevator car, a manual switch on the car for each of a plurality of landings, an additional manual switch on the car normally to control the car, hoisting motor and brake control means responsive only to joint actuation of one of said manual switches for a landing and said additional switch, to cause start of the car, responsive to the actuation of said additional switch to stop position to stop the car at will, and responsive to actuated manual switches for said landings to cause automatic stops of the car at said landings in their natural order.

47. An elevator system comprising an elevator car, a manual switch for each of a plurality of landings, an additional switch on the car normally to control the car, and hoisting motor and brake control means consisting of directional means responsive to said manual switches for the landings to establish direction for car movement and requiring actuation of said additional switch on the car to cause start of the car in a direction predetermined by actuation of one of said manual switches for the landings, said switches for the landings at the same time being effective to cause stops of the car at landings in their natural order regardless of the order in which switches for the landings are actuated.

48. An elevator system comprising an elevator car, a manual switch for each of a plurality of landings, an additional switch on the car normally to control the car, and hoisting motor and brake control means comprising directional means responsive to said manual switches for the landings to establish direction for car movement and requiring actuation of said additional switch on

the car to cause start of the car in the direction predetermined by actuation of said switches for the landings.

49. An elevator system comprising an elevator car, a manual switch on the car for each of a plurality of landings, an additional switch on the car normally to control the car, hoisting motor and brake control means responsive to said manual switch for each landing, to cause start of the car and to stop it at landings in their natural order, and means on the car to render said switches for landings effective to cause start and stop of the car to the exclusion of said additional switch on the car, or to render switches for the landings effective jointly with said additional switch on the car to control the start and stop of the car.

50. An elevator system comprising an elevator car, a manual switch at each of a plurality of landings, a manual switch on the car for each of the landings, an additional manual switch on the car normally to control the car, hoisting motor and brake control means responsive to said additional switch on the car to cause start of the car, and at the same time responsive to said switches both at the landings and on the car to cause stop of the car at landings without changing position of said additional manual switch from its running position.

51. An elevator system comprising an elevator car, a manual switch at each of a plurality of landings, a manual switch on the car for each of the landings, an additional manual switch on the car normally to control the car and having stop and running positions, hoisting motor and brake control means responsive to said additional switch when in its running position to cause start of the car and when in its stop position to stop the car; and at the same time responsive to said switches for the landings both at the landings and on the car, to cause stop of the car at landings without changing the position of said additional switch on the car from its running position.

52. An elevator system comprising an elevator car, a manual switch at each of a plurality of landings, a manual switch on the car for each of said landings, an additional switch on the car normally to control the car, hoisting motor and brake control means so arranged that joint actuation of a manual switch for one of the landings and said additional switch is necessary to cause start of the car, and being responsive at the same time to cause stops of the car at landings for which switches are operated.

53. An elevator system comprising an elevator car, a manual switch at each of a plurality of landings, a manual switch on the car for each of said landings, and hoisting motor and brake control means comprising switches connected in series, one of which is in the car, certain of said series switches being responsive to said manual switches to cause automatic stops of the car at landings successively in their natural order, and the one of said series switches which is on the car being controllable to cause start and stop of the car only by manual operation and to the exclusion of said manual switches for the landings.

54. An elevator system comprising an elevator car, a manual switch at each of a plurality of landings, a manual switch located on the car for each of said landings, an additional manual switch on the car normally to control the car, hoisting motor and brake control means responsive to said switches at the landings and on the

- car excepting said additional manual switch, to cause start of the car and to intercept it at the landings successively in their natural order, regardless of the order in which they are actuated, 5 and means to render said manual switches for the landings effective to control the car in the aforesaid manner to the exclusion of said additional switch, or to render the control of the car subject to joint control by said switches for the 10 landings and said additional switch on the car.
55. A control system for an elevator car comprising control means at each of a plurality of landings, control means on the car for each of said landings, a car switch on the car having stop 15 and running positions, and a hoisting motor and brake control means responsive to said car switch when in running position to cause movement of the car and to cause stop of the car when said car switch is in stop position, and responsive to 20 said landing control means both on the car and at said landings to intercept the car without changing the position of the car switch from its running position.
56. A control system for an elevator car comprising a manual switch at each of a plurality of landings, a manual switch on the car for each of said landings, an additional manual switch on the car normally to control the car, hoisting motor and brake control means responsive to said 25 manual switches on the car and at the landings to intercept the car at landings in their natural order, regardless of the order in which said manual switches for the landings in advance of car movement are actuated, and at the same time responsive to said additional switch on the car, and means to condition said motor and brake control means to be subject to control of said 30 manual switches for the landings on the car and at the landings to the exclusion of said additional switch on the car.
57. In a control system, the combination with the car, a hoisting motor therefor, a car switch to control said motor to start the car, a plurality of push-button switches within the car, one for each of a plurality of landings, floor-relays each having a winding and an energizing circuit therefor responsive to operation of its corresponding car push-button switch within the car, all of said windings corresponding to landings ahead of the 45 car being energizable at any time and each having a self-holding circuit maintained independently of the others, car control circuits controllable by said floor relays and in accordance with position of the car, means controllable by the car to re-set said floor-relays by opening their self-holding circuits, said car control circuits being first broken and then re-established by movement of said floor-relays, to normal position 50 successively in accordance with position of the car.
58. In an elevator control system having means operable in accordance with the position of the car with respect to the floors for automatically causing movement of the car to and stopping the car accurately at the floor levels, attendant controlled means movable to one position to cause said car to run and movable to another position to render said automatic leveling and stopping means effective to normally cause the car to stop, 55 means effective when the attendant control means is moved to normal stop position and the car is within a predetermined distance above or below a landing to stop said car at the said floor level, a passenger controlled signal system and

means operable thereby to render said leveling and stopping means effective independent of the position of said attendant controlled means.

59. In a control system for an elevator car operable past a plurality of floors, a passenger call system including a passenger actuatable switch at each floor for registering a call for service at that floor and means operable in accordance with the position of the car with respect to said floors for cooperation with said passenger controlling switch, control switch means for controlling the running of the car, a circuit therefor, a car switch on said car operable to one position to complete said circuit to start said car and operable to another position to break said circuit, 10 and means operably responsive to the combined actuation of said passenger controlled means and said cooperating car position means for breaking said circuit independent of the position of said car switch.

60. An elevator system comprising an elevator car, a control switch for each of a plurality of landings, a switch on the car normally to control the car and hoisting motor, and brake control means arranged so that joint actuation 15 of an annular switch for a landing other than that for the landing at which the car is stopped, and said switch on the car, is necessary to complete start of the car.

61. An elevator system comprising an elevator car, a remote controlled switch for each of a plurality of landings, means on the car for selectively controlling said remote control or landing switches, a switch on the car normally to control the car, and hoisting motor and brake control means arranged so that joint actuation 25 of a remote controlled switch for a landing other than that for the landing at which the car is stopped and said switch on the car, is necessary to complete start of the car.

62. In a system of control for elevator cars, the combination with the car of means to move the car to service a plurality of landings, car control means effective to cause start and stop of the car, said car control means including car gate actuated contactors, the car control means being effective to start the car only in response to opening and subsequent closing of said contactors following each stop of the car.

63. In a push button system of control for intercepting an elevator, the combination with the car, a hoisting motor, control means for the motor having an operating winding, and control switch mechanism, means to control said switch mechanism to effect automatic stop selectively at landings towards which the car is moving comprising push button controlled floor relay switches connected in series by a circuit including said winding for the control switch mechanism.

64. In a system of elevator control, an elevator car, motive means to move the car to service a plurality of landings, a control circuit effective to cause start and stop of the car and including landing switches, a car gate switch, and a remote controlled switch mechanism effective to cause operation of said motive means in either direction, and means for rendering said remote controlled switch mechanism responsive only to said landing switches for stopping the car and responsive jointly to said landing switches and subsequent opening and closing of the car gate switch for starting the car.

65. In a push button system of car control for

elevators, a car, motive means for moving the car to service a plurality of landings, control circuits effective to cause start and stop of the car, dual push button control means for said circuits positioned respectively at the landings and in the car, said landing and car push buttons being

normally operative jointly to control car movements, and means effective only when all landing buttons are in normal position to render only the car buttons effective to control the car control circuits to govern car movement.

ERNEST L. GALE.
